UNITED STATES PATENT OFFICE.

FREDERICK WILLIAM FARRAR, OF LEICESTER, ENGLAND, ASSIGNOR TO UNITED SHOE MACHINERY CORPORATION, OF PATERSON, NEW JERSEY, A CORPORATION OF NEW JERSEY.

SEAM-RUBBING MACHINE.

Application filed October 21, 1920. Serial No. 418,549.

To all whom it may concern:

Be it known that I, FREDERICK WILLIAM FARRAR, a subject of the King of England, residing at Leicester, Leicestershire, England, have invented certain Improvements in Seam-Rubbing Machines, of which the following description, in connection with the accompanying drawings, is a specification, like reference characters on the drawings indicating like parts in the several figures.

This invention relates to seam rubbing machines and is herein illustrated as embodied in a machine of the type set forth in United States Letters Patent No. 1,259,134, granted on application of W. T. B. Roberts March 12, 1918, filed June 26, 1916.

One of the objects of the invention is to provide a machine of this character which will enable better work to be produced and which will call for less skill and experience on the part of the operator. Heretofore, in the operation of seam rubbing machines, the difficulty has arisen that the seams are not properly opened up and the two upstanding raw edges of the work are apt to be turned down, both on the same side of the seam. To overcome this objection, one feature of the invention consists in the provision of a rotary plow which aids in feeding, and spreads the margins of two pieces of work where they project beyond the seam uniting them, and a work support having a ridge which engages between and separates the work pieces on the other side of the seam. In the illustrated embodiment, there is also provided a rotary feed roll which may be formed in sections, preferably arranged to engage the work pieces yieldingly at the sides of the ridge.

Another object of the invention is to provide an improved work support which will enable "closed" boot uppers or other work to be placed easily in a position to have the seams rubbed, the construction being such that the work also may be removed readily from the machine when the rubbing instrumentalities have completed their work. In accordance with this feature, there is provided an upright post having a shelving work surface over which "closed" boot uppers or other work may be threaded, and means to depress the post to provide for removal of the completed work.

Referring to the drawings:

Fig. 1 is a front elevation, partly in section, of the complete machine;

Fig. 2 is an elevation, partly in section, of the rotating feed shaft and its associated parts;

Fig. 3 is a detail view of a portion of the parts shown in Fig. 2 illustrating diagrammatically their presumed mode of action upon the work;

Fig. 4 is a top plan view, partly in section, of the rotating feed shaft and associated parts;

Fig. 5 is an enlarged side elevation, partly in section, of the work support;

Fig. 6 is a front elevation of a portion of the work support;

Fig. 7 is a detail section showing the manner of adjusting the height of the work support.

The framework of the machine, including the shafts and drive gearing for the rotating tools, is, or may be, similar to the structure shown in the Roberts patent above referred to. It comprises a projecting arm or gooseneck 8 which carries, in suitable bearings in a bracket 14, a shaft 10 having on one end a work rubbing roll or flattening tool 12. The bracket 14 may be pivotally mounted to swing on the trunnions 16 and in order to hold the rubbing roll 12 yieldingly against the work a spring 18 may be interposed between the bracket and the framework.

Referring more particularly to Figs. 2 and 3, where my seam opening and guiding device is shown in detail, there is provided a driven feed shaft 20 on which is mounted a feed roll comprising conical sections 22 and 24 adapted to form, in co-operation with the inclined faces of the block or anvil 60, hereinafter referred to, a substantially parallel sided inverted V-passage 26 for the work. The conical portions are truncated so as to have narrow annular faces 28 at their smaller ends and on the driven shaft 20 between these faces, there is formed a seam opening and feed member comprising a peripheral rib or plow member 32 of a diameter slightly larger than the diameter of the narrow faces 28 and gradually increasing in thickness from its portion of greatest diameter to that portion of it which joins the driven shaft. The driven shaft 20 is formed at each side of the rib 32 with 105 110

shoulders 34 which form stops to limit the movement of the spring pressed conical sections 22, 24 towards the peripheral rib 32. Thus there are small spaces between the 5 narrow faces 28 and the sides of the rib 32, these spaces being provided to prevent stray ends of thread and the like from being pinched and caught between the narrow faces and the rib. The conical sections are 10 urged axially towards the rib by springs 36 interposed between the ends of the sections and collars 38, 40 fast on the driven shaft 20. The conical sections 22, 24 are constrained to rotate with the driven shaft 20 15 by pins 42, 44, respectively, projecting axially from the fixed collars 38, 40 and entering openings in the conical sections.

To drive the feed roll, the driven feed shaft 20 may be connected to, or formed 20 integrally with, a drive shaft 46 mounted in bearings 48 and 50 on a bracket 52, pivoted as indicated at 54, to the framework. To press the feed roll downwardly against the work, the spring 56 may be interposed between 25 the framework and the bracket 52. At 58 in Fig. 4 is indicated a pressing or ironing roll and this roll, together with the drive shaft 46, may be supported and driven as described in the Roberts patent 30 referred to.

Referring more particularly to Figs. 5 and 6, the block or anvil 60 which constitutes the work support is provided with two faces 62 inclined to each other and 35 meeting in a ridge 64 back of which is a flattened portion 66 which receives the pressure of the work rubbing roll. The block 60 has on its lower face a tongue which is clamped in a dovetailed groove 68 formed 40 in the upper face of a vertically sliding upright post 70 mounted in the casing 72. The block 60 is clamped in the post 70 by clamp screws 74 and is adjustably fixed in 45 position by a screw 76 threaded into the block and having its head in engagement with a face of the post 70.

To actuate the post 70 to apply or remove the work, there is provided in its lower end a recess in which is pivoted one end of the 50 link 78, the other end of the link being pivotally connected to a lever 80 pivoted in the casing. The lever 80 is pivoted on an eccentric portion 82 of a stud 84 which is rotatably mounted in bearings on the 55 casing. To adapt the machine for different varieties of work, this stud is provided with a head 86 by which it may be rotated to adjust the post 70 vertically. The stud may be locked in its adjusted position by a 60 nut 88 on one end. The block 60 is held in a normal raised position by a spring 90 fastened at one end to a hook 92 and at the other end to an arm 94 of the lever 80. A 65 face 96 on the lever and a pin 98 on the casing limit the height of the block, the

parts being normally in a position in which the link 78 and the arm of the lever 80 to which it is coupled, constitute a more or less straightened toggle supporting the block against heavy downward pressure. 70 To lower the block 60 for removal of work the lever 80 has pivotally connected to it at 100 a treadle rod 102, and to limit this movement, there are provided a lug 104 on the lever 80 and a stop face 106 on the 75 casing. The contour of the block is shelving and is such that a "closed" boot upper or the like can be threaded conveniently over it as the work passes beyond the point of operation. The work pieces may also 80 be withdrawn alone or with others when a number of them have thus accumulated on the block, this being accomplished by a depression of the treadle rod to provide the necessary clearance between the post and 85 the rotating rolls.

In operation, when the leading edge of a piece of work W (fed up the ridge of the block 66 by the operator) encounters the feed roll, the conical sections 22, 24 90 will be forced apart by the portions of work lying on the inclined faces 62 of the block, and the rib 32, which is in line with the ridge of the anvil, will enter between the upwardly projecting raw edges of the two 95 pieces of material W joined by the seam, as shown in Fig. 3. These edges will thus be fed and definitely spread apart in opposite directions away from the seam in preparation for the action of the rubbing 100 tool or other flattening device.

Although the invention has been set forth in connection with a machine for pressing seams and has been described as particularly adapted for use in shoe manufacture, 105 it should be understood that the invention is not limited in the scope of its application to the particular machine which is shown and described nor to use with any particular material.

Having thus described my invention, what I claim as new and desire to secure by Letters Patent of the United States is:

1. In a seam rubbing machine, a work support having a ridge to separate the work 115 pieces on one side of the seam, and a mechanically actuated plow to feed and separate the margins of the two pieces of work where they project beyond the seam.

2. In a seam rubbing machine, a work support, a rotary shaft, and a device positively actuated by the shaft progressively to separate the margins of two pieces of work where they project beyond the seam, 120 said device comprising an annular plow and yieldingly mounted feed rolls on opposite sides of the plow.

3. In a machine of the class described, the combination with a work support having a ridge, of rotary members mounted for rela- 130

tive yielding axial movement to engage the work on each side of the ridge.

4. In a seam rubbing machine, a work support, a rotary shaft, feed members mounted to slide axially on the shaft, and spring means arranged to move the members axially to press them yielding against work on the support.

5. In a seam rubbing machine, a stationary work support, a rotary shaft, and feed members mounted on the shaft for yielding axial movement.

6. In a seam rubbing machine, a work support having a ridge, a rotary shaft, and a driven feed roll comprising two conical portions yieldingly urged toward one another to press the work on the sides of the ridge.

7. In a machine of the class described, a work support having a ridge, a rotary shaft, and a driven feed roll mounted on the shaft and comprising relatively axially yieldable conical portions arranged to press the work on the sides of the ridge.

8. In a seam rubbing machine, a work support, a rotary shaft, conical members slidably mounted on the shaft, and means to press the conical members toward each other.

9. In a seam rubbing machine, a work support, a rotary shaft having a plow, conical members slidably mounted on the shaft, springs to press the conical members toward each other, and means to limit the approach of the conical members toward the plow.

10. In a seam rubbing machine, the combination with a work support, of a rotary plow, and yielding means acting on the work at the side of the plow to press the work toward the plow.

11. In a seam rubbing machine, a work support having a ridge, a rotary plow, and feed members mounted to rotate with the plow and constructed and arranged to press yieldably towards the sides of the ridge.

12. In a seam rubbing machine, a plow, and a driven, work-feeding member comprising relatively axially movable sections to engage the work at the sides of the plow.

13. In a seam rubbing machine, the combination with a work support having a ridge, of a rotary member having a peripheral rib, and conical members at the sides of the rib to press the work on the sides of the ridge.

14. In a seam rubbing machine, the combination with a support having a ridge, of a rotary plow, and means coaxially arranged with respect to the rotary plow for yield-

ably engaging the work at the sides of the plow.

15. In a seam rubbing machine, a work support having a ridge, a plow, and rotary members mounted for yielding axial movement to engage the work at the sides of the ridge.

16. In a seam rubbing machine, a work support having a ridge, a rotary shaft having a rib to enter between the margins of two pieces of work where they project beyond the seam, and rotary members mounted on the shaft for relative yielding movement to engage the work on each side of the ridge.

17. In a seam rubbing machine, the combination with a work support having a ridge, of a work feeding roller comprising relatively yieldable sections to engage the work at the sides of the ridge, said feed roller sections also having provision for yielding in a direction transversely of their axis.

18. In a seam rubbing machine, a rubbing tool, an upright post having a stationary shelving work surface over which "closed" work may be threaded as the seam is rubbed, and means to depress the post to provide clearance between the latter and the rubbing tool for the withdrawal of the work.

19. In a seam rubbing machine, a rubbing tool, an upright post over which "closed" work may be threaded as the seam is rubbed and having a work-supporting surface consisting of a ridge merging into a plane, means to sustain the post rigidly against the rubbing pressure, and means to release the sustaining means to depress the post for removal of the work.

20. In a seam rubbing machine, a rubbing tool, a post over which "closed" work may be threaded as the seam is rubbed and having a work-supporting surface consisting of a ridge merging into a plane, a toggle to sustain the post rigidly against the rubbing pressure, and means to break the toggle to depress the post for removal of the completed work.

21. In a seam rubbing machine, a rubbing tool, a work supporting post over which "closed" work may be threaded as the seam is rubbed, a toggle to sustain the post rigidly against the rubbing pressure, means to adjust the position of the toggle, and means to break the toggle to depress the post.

In testimony whereof I have signed my name to this specification.

FREDERICK WILLIAM FARRAR.
